GRINDING WHEEL TRUING APPARATUS

Lloyd E. Paine, Worcester, Mass., assignor to
 Norton Company, Worcester, Mass., a corpora-
 tion of Massachusetts

Application September 30, 1938, Serial No. 232,604

1 Claim. (Cl. 125—11)

The invention relates to grinding wheel truing apparatus.

One object of the invention is to provide a truing apparatus for grinding machines so organized that two different surfaces on a grinding wheel may be dressed and trued with a given setting of the machine, and without removing the work piece from the machine centers. Another object of the invention is to provide a simple and practical truing attachment which may be readily mounted on existing machines. Another object of the invention is to provide truing apparatus mounted on the face plate of a grinding machine so that a minimum of adjustment will be required for the truing operation. Another object of the invention is to improve a grinding machine with an angular slide so as to facilitate the truing of both peripheral surfaces of the grinding wheel. Other objects will be in part obvious or in part pointed out hereinafter.

The invention accordingly consists in the features of constructions, combinations of elements, and arrangements of parts, as will be exemplified in the structure to be hereinafter described, and the scope of the application of which will be indicated in the following claim.

In the accompanying drawings in which is shown one of many possible embodiments of the mechanical features of this invention:

Figure 1 is a front elevation of a grinding machine equipped with the wheel truing apparatus of the invention;

Figure 2 is a plan view of the machine;

Figure 3 is an enlarged view of the truing tool; Figure 4 is a view similar to Figure 2 with the wheel truing tool in place;

Figure 5 is a front view of the face plate 20 taken along the line 5—5 of Figure 4.

Referring first to Figure 1, the invention may be applied to a cylindrical grinding machine of any type, but so far as certain features of the invention are concerned, it is applied to a machine having a wheel head journaling the grinding wheel spindle at an angle with the axis of the work piece. Such a machine has a base 10 on the upper surface of which, as shown in Figure 2, are parallel ways 11 and 12 mounting a work table 13 upon which are clamped a headstock 14 and a tailstock 15. The tailstock 15 is provided with the usual adjustable tail center 16, while in the headstock is mounted a spindle, not shown, driven by a motor 17 through belts and pulleys contained in a casing 18. On the front of the spindle which is journalled in the headstock is the usual face plate 20 which is provided with a

number of the usual radial T-slots, for example the T-slot 21 shown in a broken away portion of the face plate 20 in Figure 2. Projecting from the face plate 20 and coaxial with it is the usual head center 22.

The machine may be equipped with any usual or preferred mechanisms for traversing the table 13 along the ways 11 and 12. For example, there may be provided, as shown in Figure 1, a rack 24 secured to the under side of the table or carriage 13 with which meshes a pinion gear 25 fastened to a stud shaft 26 which has likewise fastened to it a gear 27 which meshes with a pinion gear, not shown, on the shaft of a hand wheel 30. Thus, the operator, by turning the hand wheel 30, may readily traverse the table or carriage 13 and with it the work piece W, but it will be understood that mechanical or hydraulic traversing mechanisms might be substituted.

The machine is equipped with a cross slide 35 mounted on the usual ways, not shown, and having secured on its under side, as shown in dotted lines in Figure 2, a half nut 36 engaged by a cross feed screw shaft 37, a non-threaded part of which extends to the front of the machine and has there fastened to it a gear 38 meshing with a gear 39 (shown in dotted lines in Figure 2), which gear, as best shown in Figure 1, meshes with a pinion 40 fastened to a ratchet wheel 41 which may be operated by a pawl 42 that is capable of being moved manually or automatically by means of a solenoid 43. The foregoing or any other suitable cross feeding mechanism is provided to feed the wheel slide 35 in a direction transverse to the direction of movement of the table or carriage 13. Usually such transverse direction is a direction perpendicular thereto, as illustrated in the present case.

For the grinding of shafts with shoulders or the like, it is desirable to provide an apparatus 40 which will grind the cylindrical portion of the shaft as well as the radial shoulder itself and will grind each of them to the corner. The machine accordingly is provided with a grinding wheel 45 whose periphery constitutes two conical surfaces 46 and 47, the included angle of the cones being 90° and elements of the cones being at angles of 45° to the axis of the wheel and the conical surfaces being of like dimensions and area. This wheel is mounted upon a wheel spindle 50 journalled in a wheel head 51 with the axis of the spindle at 45° to the axis of the screw shaft 37. Mounted on the wheel head 51 is a motor 55 connected to the spindle 50 by suitable belts and pulleys all encased in a casing 60.

According to the present invention I provide a truing tool having one or more wheel truing points (preferably diamonds), which truing tool may be mounted in a T-slot 21 of the face plate 20. As shown in Figure 3, this truing tool comprises a stud 70 having an enlarged threaded portion 71 and a head 72. I provide a nut 73 fitting on the threaded portion 71 together with a washer 74. At the left-hand end of the stud 70 is an axial hole 75. Near the left-hand end of the stud 70 is a transverse hole 76. I provide a diamond truing nib 77. This nib has a shank 79 which will fit in either of the holes 75 and 76. Set screws 81 and 82 hold the nib 77 in place by engagement with the shank 79. The nib 77 has an embedded diamond 83 for truing the wheel 46.

The work piece W shown is a shaft having an irregular end portion W' the face of which is to be ground to a plane surface, the shaft of the work piece being ground to a cylindrical surface. The stud 70 functions as a work driving dog to rotate the work piece as shown in Figure 2. Considering the parts in the position shown in Figure 2, the operator can quickly 20 rotate the ratchet wheel 41 (by hand) feeding the grinding wheel into the work piece and can readily grind the left hand face of the part W' as well as the cylindrical surface of the work piece W. When the operator desires to true 25 the grinding wheel he first stops the rotation of the work piece with the truing tool 70 in the horizontal plane of the center 22 and on the back side of the work piece then advances the work piece a quarter turn. The parts can be 30 put in this position in any manner desired. This clears the work piece away from the truing tool. Assuming that the nib is in the hole 75 the operator can readily true the face 47 of the grinding 35 wheel by moving it across the face of the nib. Then he can shift the nib to the hole 76 and true 40

the other face 46 of the grinding wheel. He may then proceed to grind the same or a different work piece with a minimum of adjustment of the machine.

The practical advantage of the present invention lies in the fact that the grinding wheel is always very close to the truing device thus making the truing a matter of a moment. Furthermore the grinding wheel can be trued with the work piece still mounted in the machine or work pieces can be removed from the machine without upsetting the set-up for the truing operation. The brake in the work head holds the truing tool rigidly enough for the truing operation. The truing tool has a double function as a truing 15 tool and a driving dog. The subject matter of the invention is particularly advantageous when embodied in hand traverse grinders where a simple set-up is important for speedy operation and effective control.

It will thus be seen that there has been provided by this invention an apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth, or shown in the accompanying drawings is to be interpreted 20 as illustrative and not in a limiting sense.

I claim:

In a grinding machine, a work head, a rotatable face plate, a stud, means to hold said stud in the face plate to act as a driving dog, means in the stud to hold a truing nib, a cross slide, and a wheel spindle mounted at an angle on said cross slide.

LLOYD E. PAIN. 40
